Primary Examiner—Antoine Duval Davis

(73) Assignee: **Appa Technology Corp.**, Taipei Hsien (TW)

(74) Attorney, Agent, or Firm—Dougherty & Troxell

(**) Term: **14 Years**

CLAIM

(21) Appl. No.: **29/130,755**

The ornamental design for an electrical multimeter with a stand, as shown and described.

(22) Filed: **Oct. 6, 2000**

DESCRIPTION

(51) LOC (7) Cl. **10-04**
(52) U.S. Cl. **D10/78**
(58) Field of Search D10/78; 324/72.5,
324/110, 114, 115, 149, 151 A, 151 R,
156, 158 F

FIG. 1 is a perspective view of the electrical multimeter with a stand showing the new design;

FIG. 2 is a front view of the new design;

FIG. 3 is a rear view of the new design;

FIG. 4 is a left view of the new design;

FIG. 5 is a right view of the new design;

FIG. 6 is a top view of the new design;

FIG. 7 is a bottom view of the new design; and,

FIG. 8 is a perspective view of the new design showing the status that the stand is in use.
